UNITED STATES PATENT OFFICE

THEODORE LANBACH NEUMANN, OF DAYTON, OHIO, ASSIGNOR TO THE DAYTON PAPER NOVELTY COMPANY, OF DAYTON, OHIO, A CORPORATION OF OHIO.

PAPER BOX.

1,106,831.

Specification of Letters Patent. Patented Aug. 11, 1914.

Application filed February 7, 1911. Serial No. 607,210.

To all whom it may concern:

Be it known that I, THEODORE L. NEUMANN, a citizen of the United States, residing at Dayton, in the county of Montgomery and State of Ohio, have invented certain new and useful Improvements in Paper Boxes, of which the following is a specification.

My invention relates to an improvement 10 in cardboard boxes of collapsible form.

One of the objects of my invention is to provide a collapsible cardboard box, in which the sides fold inward and in which two opposing sides are scored and slit so 15 that portions of each thereof fold upon one another to permit the remainder sides of the box to overlap each other in knock-down position.

Another object of my invention is to provide a collapsible box with inwardly folding sides, with two of the opposing sides scored and slit to permit overlapping of the remainder sides into collapsed form, with reinforcing means adapted to overlap the slit 25 portion of said sides for supporting the same in set up position.

Another object of my invention is to provide simple and convenient means for securing a tape or cord to the sides of the box in 30 a secure and reënforced manner without requiring additional features other than employed in the production of my improved box.

The features of the invention are more 35 fully set forth in the description of the accompanying drawings, forming a part of this specification, in which:—

Figure 1 is a perspective view of my box in set up position. Fig. 2 is a central vertical section through the box taken through the sides divided by scored lines and slits, to provide overlapping portions thereof. Fig. 3 is an enlarged detail sectional view of a portion of the sides. Fig. 4 is a top plan 45 view of the box partially collapsed. Fig. 5 is a detail side elevation of the medial upper portion of one of the scored sides.

I am aware that rectangular collapsible boxes with the sides adapted to fold inwardly have been heretofore manufactured, but in such instances, the sides did not equal in area one-half the area of the base, or of such size that two opposing sides overlap each other. With my improved box, the 50 combined area of the opposing sides is

greater than the base to enable the formation of a deep box irrespective of its width.

1 represents the base of the box; 2, 3, two opposite rigid sides adapted to remain flat when the box is either set up or knocked down. 4, 5 represent the other two sides of a rectangular box, which are divided from the base by scored lines. The sides 4, 5, carry corner-flaps 6 which are secured to the sides 2, 3, in any usual manner. 65

In order to distinguish the sides 4, 5, from the unscored sides 2, 3, I term the same divisional sides for the reason that they are provided with the oblique scored lines 7, 8, running diagonally from the respective base 70 corners toward the medial upper edge of the sides, so as to divide said sides 4, 5, into triangular divisions, *a*, *b*, *c*, when folded.

9, 10, represent curved slits commencing at the terminals of the scored lines 7, 8, and extending outward toward the edge of said sides. The slits determine the contiguity of the divisional folds along the diagonal lines toward the medial portion of the sides, and allow the rigid sides to engage into such 80 slits, providing a clearance, and allow the divisions to overlap the rigid sides. 75

11 represents a U-shaped reinforcing strip secured to the intermediate section of the sides, preferably by staples 12, 13, and with 85 the inner portion of said strip preferably of greater area or size than the outer limb, and with the edges preferably rounded. This reinforcing strip overlaps the slits to maintain the sides in a rigid vertical position 90 when the box is set up.

14 represents a tape or string, serving as a tie for the cover of the box, and it is preferably secured in position, as follows:— In each of the intermediate portions or divisions of the sides 4, 5, is cut a vertical slit 15, see Fig. 5, through which a tape is passed and knotted at one end. The tape is adapted to project between the outside limb of said reinforcing strip and said intermediate section, and preferably between the staples securing said reinforcing strip. This forms a convenient method of securing the tape in position, and as the slit edges are maintained against distortion relative to 100 each other by the reinforcing strip, the tape is securely held in position. 105

To fold the box to its knock down position, the reinforcing strip is of such size and cut, that by pressing the sectional fold- 110

ing sides inward, to fold the outer triangular sections upon the intermediate section of each side, inward pressure is brought on the intermediate section of each side, causing the outer limb of the reinforcing strip to yield sufficiently to permit the outer triangular sections to become disengaged from beneath the reinforcing strip and fold upon the intermediate portion, along the diagonal 10 scored lines, with the portion of the intermediate section between the slits remaining flat.

To more clearly understand such folding operation, reference is had to Fig. 4. This 15 view shows the sides 4, 5, folded inward, with the reinforcing strip 11 disengaged from the triangular sections. The left hand side, or the right, as desired, is pressed down in advance of the other so as to overlap each other, whence the side 3 is folded so as to come beneath the slit edge of the 20 sections b of the sides 4, 5, and the opposite side 2 with the sections b overlapping the side 3.

25 Having described my invention, I claim:—

1. A collapsible box having two opposing non-scored sides, two opposing scored and slotted sides, each subdivided by two 30 diagonal scored lines extending from the base corners toward each other terminating at

points short of their intersection and continuing with diverging slotted lines to the upper edge, said slits determining the contiguity of the folds when overlapping the end 35 divisions of a side upon the exterior surface of the intermediate division, and provide clearance for the reception of a non-scored side.

2. A collapsible box having two opposing 40 non-scored sides, two opposing scored and slotted sides each subdivided by two diagonal scored lines extending from the base corners toward each other terminating at 45 points short of their intersection and continuing with diverging slotted lines to the side upper edge, said slits determining the contiguity of the folds when overlapping the end divisions of a side upon the exterior 50 surface of the intermediate division and provide clearance for the reception of a non-scored side, and a marginal strip for each scored side overlapping both faces thereof for maintaining the rigidity of the sides when non-folded.

55 In testimony whereof, I have hereunto set my hand.

THEODORE LANBACH NEUMANN.
